ANTENNA SYSTEM

David E. Sparks, Chicago, Ill., assignor to Belmont
Radio Corporation, Chicago, Ill., a corporation
of Illinois

Application February 23, 1940, Serial No. 320,247

3 Claims. (Cl. 250—11)

This invention relates to radio antenna systems and in particular to double loop antenna systems.

With progress in the radio art evidencing itself, in more sensitive and selective receivers, there has been likewise public demand for increasingly improved quality in reproduction. In many instances, the improvement in the radio receiver circuit has been lost, by the radio user connecting the receiver to an inadequate or improperly designed antenna system, which in turn has seriously affected the reproduction from the receiver. In attempting to counteract this difficulty and at the same time to fulfill the demand for greater compactness and portability in radio apparatus, loop antennae have been incorporated directly into the receiving housing, or have been connected with the housing in such a way as to be moved therewith.

Single loop antenna systems have the characteristic feature of effecting an induced voltage, due to an oncoming wave, which is directly proportional to the frequency of such wave. This characteristic gives a rising voltage over the broadcast or receiving range so that the signal pick-up over the wave spectrum is not entirely satisfactory because of the variable signal gain over the spectrum; a low signal response occurring at the low frequency end of the wave spectrum and a high signal response occurring at the high frequency end thereof.

It is an object of this invention, therefore, to provide an improved loop antenna system for radio receiving apparatus.

It is another object of this invention, to provide a loop antenna system for radio receivers which substantially eliminates the undesirable characteristics common to loop antenna systems, now in commercial use.

It is a further object of this invention to provide a loop antenna system which operates to effect maximum attenuation at some undesired frequency.

It is still another object of this invention to provide a loop antenna system which operates to effect maximum attenuation at some undesired frequency and a substantially uniform signal response over a desired wave band.

It is a particular object of this invention to provide a double loop antenna system which combines all of the advantages of a single loop antenna system for a radio receiver as to installation and compactness, with improved operating characteristics, to in all provide a compact radio receiver operating effectively to produce a sub-

stantially uniform signal response over an entire band of frequencies.

Other objects, features and advantages of this invention will be apparent from the following description taken with the drawing in which:

Fig. 1 is a diagrammatic illustration of a representative radio receiver system employing the double loop antenna system of the invention.

Fig. 2 is a circuit diagram illustrating a modified arrangement of the invention.

Fig. 3 is a circuit diagram illustrating a further modification of the invention.

Fig. 4 shows in curve form some of the operating characteristics of the antenna systems shown in Figs. 1, 2 and 3, and

Fig. 5 illustrates diagrammatically one method of assembling the loops included in the antenna systems of Figs. 1, 2 and 3.

In practicing this invention there is provided a radio receiver system including a pair of loop aerials, which are electrically connected in a manner to effect complementary operating characteristics. In the operation of the antenna system it is contemplated that one of the loops have a higher inductance than the other with the circuit arrangement of the loops being such that the maximum signal pick-up for each loop will not occur at the same wave frequencies, the loop having the lesser inductance being most effective at the high end of a band of frequencies being received and the loop of larger inductance being most effective at the lower end of such band of frequencies. The loops are not limited as to their physical size and may vary in their relative structure. However, for the purpose of simplicity and convenience of explanation the loops in the following description will be considered as having the same physical dimensions.

In the drawing similar characters of reference shall be used in the various figures to designate similar parts. With reference to Fig. 1, there is shown an antenna circuit with loops L_1 and L_2 and condenser C_1 in series connection. The voltages induced in the loops L_1 and L_2 by the incident wave are illustrated, for the purpose of clarity and convenience, as being generated by generators E_1 and E_2 , respectively. An inductance L_3 and a capacity C_3 are connected in series across the loop L_2 ; the signals picked up being taken off across the capacity C_3 by conductors 10 and 11, conductor 10 connecting L_3 in series with the grid 12 of the RF or converter tube 13, which constitutes the first tube stage in the receiver circuit. The remainder of the circuit is substantially conventional including the RF or IF am-

plifier, the detector, and the AF amplifier which are designated by the appropriate abbreviation in the illustration. A speaker 14 is connected to the audio-frequency amplifier in a normal manner. The resistor 17 provides a bias for the grid 12 and the capacitor 18 provides a low impedance path to the ground.

Referring specifically to the antenna circuit of Fig. 1 the features of the invention are found in the novel arrangement and conditioning of the loops L_1 , L_2 and capacity C_1 . The additional elements in this circuit merely indicate a manner of connecting the loops L_1 and L_2 to a utilization circuit, which is illustrated as including the elements L_3 and C_3 , the connecting terminals being shown at B-B. The antenna circuit per se is not tunable, but resonance of the system is obtained by varying the tuning elements L_3 or C_3 in the utilization circuit. This tuning may be obtained by a variation of the capacitance C_3 with a fixed inductor L_3 , by a variation of the capacitance C_3 with L_3 equal to zero and L_2 providing the necessary tuning inductance or by a variation of the inductor L_3 with a fixed capacitance C_3 , the operation of the antenna system being equally effective regardless of which of the two elements L_3 or C_3 is varied for resonant tuning. To better understand the invention and its operation the various circuit relations will be discussed in an analysis of the fundamental equations setting up these relations.

For convenience in the analysis, the antenna circuit shall refer to both loop circuits, the utilization circuit to the circuit including L_3 and C_3 and the antenna system shall include all circuits. The circuit elements and factors associated with each loop shall be suitably designated to indicate such association.

Since the determination of the signal response of the antenna system over a band of frequencies requires a determination of the character of the response, the analysis is predicated on the magnitude of the response and the conditions in the system affecting such magnitude. It is readily seen that the voltage delivered across the loop L_2 to the utilization circuit represents the magnitude of the signal response to be reproduced by the receiving apparatus. This voltage, designated as E , can be expressed in terms of E_1 and E_2 , which correspond to the voltages induced in L_1 and L_2 , respectively. Since the voltages E_1 and E_2 are assumed as connected in series opposition, the relation between them, neglecting dissipation, can be written as:

$$E_1 - E_2 = (I_1 - I_2)(Z_1 + Z_2) \quad (1)$$

and the voltage E across loop L_2 as:

$$E = E_2 + (I_1 - I_2)Z_2 \quad (2)$$

By a proper substitution of Equation 1 into Equation 2 the expression for E becomes:

$$E = \frac{E_2 Z_1 + E_1 Z_2}{Z_1 + Z_2} \quad (3)$$

where

$$Z_1 = j \left[w(L_1 \pm M) - \frac{1}{WC_1} \right] \quad (4)$$

and

$$Z_2 = jw(L_2 \pm M) \quad (5)$$

in which Equation M is the mutual coupling factor between loops L_1 and L_2 ; j is an operator equal to $\sqrt{-1}$ and $w = 2\pi f$, f representing the frequency in cycles.

The signal response of the system is thus set

up in terms of E_1 , E_2 and the impedances effected in the loop circuits. It is to be noted also from the above equations for Z_1 and Z_2 , that the loops L_1 and L_2 may be relatively positioned to obtain a mutual coupling factor of either plus or minus sign, without affecting the phase opposition of E_1 and E_2 . This change in the sign of the coupling factor can be accomplished by changing the clasps from an essentially coplanar position to an essentially coaxial position or vice versa.

Equation 3 for E , therefore, can be written in a more applicable form by substituting therein equivalents for the voltages E_1 and E_2 , which are induced in the loops L_1 and L_2 , respectively. Thus:

$$E_1 = \epsilon N_1 \mathcal{J} \sin \left(\frac{\pi S}{\lambda} \cos \theta_1 \right) \quad (6)$$

and

$$E_2 = \epsilon N_2 \mathcal{J} \sin \left(\frac{\pi S}{\lambda} \cos \theta_2 \right) \quad (7)$$

in which ϵ is the strength of the radio wave in volts per meter, S is the width of the loop in meters, $\mathcal{J}$ is the height of the loop in meters, N_1 and N_2 are the number of turns in L_1 and L_2 , respectively, and θ_1 and θ_2 are the angles of the incident wave with respect to the planes of loops L_1 and L_2 , respectively.

Since it is contemplated in the invention to use loop dimensions which are relatively small as compared to a wave length, the following relations can be written for Equations 6 and 7 with only negligible error, in which

$$\frac{1}{\lambda} = \frac{f}{C} \quad (8)$$

where f represents the frequency in cycles and C the velocity of light.

The induced voltages E_1 and E_2 of Equations 6 and 7 then become

$$E_1 = \frac{\epsilon N_1 \mathcal{J} \pi f_{01} S \cos \theta_1}{C} \quad (9)$$

and

$$E_2 = \frac{\epsilon N_2 \mathcal{J} \pi f_{01} S \cos \theta_2}{C} \quad (10)$$

The function f_{01} designates a particular definite frequency and will be hereinafter fully explained. In the present analysis, the loops L_1 and L_2 are considered for simplicity as having similar physical dimensions, but it is to be understood that the invention is not restricted to a structural similarity of the loops for its successful operation.

The expression $\epsilon \mathcal{J} \pi f_{01} S / C$ in Equations 9 and 10 represents a constant for each loop L_1 and L_2 so that these equations may be rewritten in a more simple form as

$$E_1 = T N_1 \cos \theta_1 \quad (11)$$

and

$$E_2 = T N_2 \cos \theta_2 \quad (12)$$

By substituting the values for E_1 and E_2 as formulated in Equations 11 and 12 into Equation 3, the expression for E may be written as

$$E = \frac{T(N_2 Z_1 \cos \theta_2 + N_1 Z_2 \cos \theta_1)}{Z_1 + Z_2} \quad (13)$$

From Equation 13 it is apparent that E becomes zero when

$$\frac{N_2 Z_1 \cos \theta_2}{N_1 Z_2 \cos \theta_1} = -1 \quad (14)$$

Since the factors in this expression are all variable it is seen that Equation 13 provides six pos-

sible solutions for obtaining a zero value of E , and that the functions $\cos \theta_2 / \cos \theta_1$, N_2/N_1 and Z_1/Z_2 are equally important in determining the frequency at which E is equal to zero. As noted above it is a particular feature of the invention to provide a loop antenna system which effects a maximum attenuation at some undesired frequency. Since maximum attenuation occurs when E is equal to zero, Equation 13 may be utilized to obtain an antenna system having certain operating characteristics, by assuming therein particular values for the variable functions. These characteristics may be graphically illustrated to indicate the operation of a particular system.

With reference to Fig. 4, curve III shows the operating characteristics of a particular antenna system which was designed in accordance with this invention. The values of E are represented as the ordinates and the frequency ratio of f/f_{01} as the abscissae. Curve III represents a solution to a receiving situation in which it is desired to have maximum attenuation at some undesired intermediate frequency designated as f_0 , such as a frequency of 465 kc., which occurs below the the usual broadcast range. The broadcast range or band is defined by a low frequency f_{01} and a high frequency f_{02} , the voltage gain between these limits being of a substantially constant value. Curve III, therefore, covers an antenna system which operates to effect a substantially flat signal gain over a broadcast range between the frequencies of f_{01} and f_{02} , with maximum attenuation of an undesired frequency f_0 below the broadcast range. It is to be understood that curve III illustrates the operating characteristics of only one particular antenna system and that the invention is not to be so limited.

In the use of Equation 3 for determining the arrangement of the circuit elements to effect a particular desired result, such as shown by curve III of Fig. 4, the loops L_1 and L_2 , for simplicity, shall be considered as having induced therein a maximum voltage E_1 and E_2 , so that θ_1 and θ_2 , which represent the angles of the arriving wave with respect to the planes of the loops L_1 and L_2 , respectively, are each equal to zero. Since an antenna system effecting a flat signal gain over a desired wave spectrum, with maximum attenuation at a frequency lying outside of such spectrum is desired, a better understanding of the system can be obtained if Equation 3 is expressed in terms of the frequencies defining the extent of the spectrum. Equation 4 is thus rewritten as

$$Z_1 = jw(L_1 \pm M) \left(1 - \frac{f_{01}^2}{f^2} \right) \quad (15)$$

where

$$f_{01}^2 = \frac{1}{4\pi^2 C_1 (L \pm M)}$$

With the voltage induced in each loop by the incident wave being directly proportional to the number of turns in each loop, and the loops L_1 and L_2 having been assumed as of the same physical dimensions it is further seen that $E_1/E_2 = N_1/N_2 = N$. Equations 11 and 12, therefore, may be restated to read

$$E_1 = T \frac{f}{f_{01}} N_1 \quad (16)$$

and

$$E_2 = T \frac{f}{f_{01}} N_2 \quad (17)$$

As previously noted T is equal to $\epsilon f \pi S / f_{01} C$. The factor f_{01} in Equations 16 and 17 thus can-

cel out, so that these equations are seen to express the direct proportional relation existing between the voltage induced in the loops and the frequency of the incident wave, this frequency being designated as f . By proper substitution of these equational relations in Equation 3 the signal gain may be stated to be

$$E = TN_2 N_f \frac{[(1 \pm KN) + P^1(N \pm K)]}{f_{01}(1 \pm KN) + P^1 N(N \pm K)} \quad (18)$$

in which

$$P^1 = \left(1 - \frac{f_{01}^2}{f^2} \right)$$

and K the coupling factor is

$$K = M(L_1 L_2) \frac{1}{L_1} = \frac{MN}{L_1} = \frac{M}{L_2 N}$$

In Equation 18 E becomes zero when the frequency, f_0 is

$$f_0 = \frac{f_{01}}{\left[1 + \frac{(1 \pm KN)}{N \pm K} \right]^{\frac{1}{2}}} \quad (19)$$

This value for f_0 is obtained from Equation 18 by setting the numerator portion

$$(1 \pm KN) + P^1(N \pm K)$$

equal to zero and solving for f . Since f is the general designation for the incident wave, the value of f at which E becomes zero will be the frequency of maximum attenuation and hence f_0 . By plotting Equation 18 as a function of f/f_{01} there is obtained curve III of Fig. 4, the desired flat signal gain occurring over the frequency range f_{01} to f_{02} and maximum attenuation of an undesired frequency occurring outside of this range. It is thus readily apparent that once the equational relations of the system are known, the respective occurrences of f_0 and f_{01} are rapidly ascertained.

For a better understanding of Equations 18 and 19, which express the combined effect of the complementary operation of L_1 and L_2 in providing for a system having the operating characteristics shown in curve III in Fig. 4, there is also shown in Fig. 4 curve II, which indicates the signal response of L_2 alone; when L_1 is disconnected therefrom. It is to be noted from this curve that L_2 operating alone effects the usual operating characteristics of a single loop antenna, namely, a signal gain in direct proportion to the frequency. A comparison of curve II with curve III illustrates the operating advantages obtained by the additional loop L_1 in circuit with L_2 . It is to be understood, however, that curve II does not represent the voltage contributed by E_2 to E when the loops L_1 and L_2 are connected together in a complementary operating relation.

Thus with reference to the system of Fig. 1 the voltage contributed to E by E_2 acting alone in the system, is found to be

$$E_{2A} = \frac{E_2 Z_1}{Z_1 + Z_2} \quad (20)$$

which expression plotted as a function of f/f_{01} , is shown in curve IV. Conversely the contribution to E from E_1 acting alone in the system of Fig. 1 becomes

$$E_{1A} = \frac{E_1 Z_2}{Z_1 + Z_2} \quad (21)$$

the voltage E_{1A} plotted as a function of f/f_{01} being illustrated in curve I. Since the sum of the voltage contributions E_{1A} and E_{2A} is equal to the signal voltage E , it is obvious that the sum

of curves I and IV will yield curve III. It is to be noted also that the frequency f_0 of maximum attenuation occurs when $E_{1A}=E_{2A}$.

With further reference to Equation 19, it is seen that f_{01} occurs at a frequency higher than f_0 , when K , the coupling factor is positive. However, when K is negative the occurrence of f_0 is dependent upon the absolute value of K , and f_{01} therefore may fall either above or below f_{01} . For a zero value of K , f_0 will occur at a frequency lower than f_{01} .

However, upon a reversal of one only of the generators E_1 or E_2 so that the generators are in aiding connection, the equations for curve III will not provide for a substantially uniform or flat signal gain over the desired frequency range $f_{01}-f_{02}$ (Fig. 4). Under this condition f_0 will occur at a frequency higher than f_{01} and phase or adjustment changes of K will not effect an occurrence of f_0 below f_{01} , as will now be described.

In the system of Fig. 1, therefore, let it be assumed that the polarity of one of the generators E_1 or E_2 is reversed. The equations corresponding to the Equations of 18 and 19 are then found to be

$$E = TN_2Nf \frac{[(1 \pm KN) - p^1(N \pm K)]}{f_{01}[(1 \pm KN) + Np^1(N \pm K)]} \quad (22)$$

and E becomes zero when

$$f_0 = \frac{f_{01}}{\left[1 - \frac{1 \pm KN}{N \pm KN}\right]^{\frac{1}{2}}} \quad (23)$$

which value of f_0 occurs within the zone of substantially uniform signal gain, as shown in curve III, Fig. 4, and hence is of a higher value than f_{01} . With the generators E_1 and E_2 in aiding connection the system is thus seen to be applicable to a condition where a substantially uniform signal gain over the entire frequency range is not essential, and where a troublesome signal occurs at a frequency higher than f_{01} .

In Fig. 2 there is shown a modified arrangement of the invention, in which L_1 , C_1 and C_2 are connected in series to form a primary circuit and L_2 and C_2 are connected in series to make up a secondary circuit. It is thus seen that the common coupling paths between the primary and secondary circuits include C_2 and the inductive coupling between L_1 and L_2 . The utilization circuit which includes L_3 and C_3 , is in series connection with the secondary circuit; the signal pick-up being taken off across C_3 to the receiving apparatus as above described in connection with Fig. 1. The coupling capacitor C_2 in the system of Fig. 2, which is not included in the system of Fig. 1, provides for greater flexibility in the selection of the occurrence of the frequency of maximum attenuation, since C_2 in conjunction with C_1 allows for a greater variation in the coupling between L_1 and L_2 . As noted above f_0 is moved with respect to f_{01} with variation in the coupling K between loops L_1 and L_2 so that relative movement between f_0 and f_{01} is effected by variation only of the coupling factor. Since C_2 provides for additional coupling between the loops L_1 and L_2 , it is apparent that a corresponding greater variation is obtained in the respective occurrences of f_0 and f_{01} .

Since the operation of the system of Fig. 2 is substantially similar to that of Fig. 1, only the pertinent equations will be referred to in the following circuit analysis. Thus with the generators E_1 and E_2 poled in opposition, the funda-

mental equations for the induced voltages E_1 and E_2 in the system of Fig. 2 are

$$E_1 = I_1 Z_1 - I_2 Z_m \quad (24)$$

$$E_2 = I_1 Z_m - I_2 Z_2 \quad (25)$$

in which

$$Z_m = j \left(wM - \frac{1}{wC_2} \right) \quad (26)$$

From Equations 24 and 25 the current I_2 in the loop L_2 is found to be

$$I_2 = - \frac{E_1 Z_m - E_2 Z_1}{Z_1 Z_2 - Z_m^2} \quad (27)$$

By assuming, for simplicity, that the elements in the system are dissipationless the zero value for the current I_2 may be written as

$$I_2 = 0 = E_1 Z_m - E_2 Z_1 \quad (28)$$

By suitable substitution Equation 28 is reduced to equivalent factors in a manner similar to that followed in connection with Equation 3 to provide for a determination of f_0 , the frequency of maximum attenuation. By this procedure f_0 is found to be

$$f_0 = f_{01} \sqrt{\frac{1 - \frac{C_1}{C_2}(N-1)}{1 \pm A}} \quad (29)$$

where

$$f_{01} = \frac{1}{2\pi\sqrt{L_1 C_1}}$$

and

$$A = K \sqrt{\frac{L_2 + L_3}{L_2}}$$

The sign to be applied to A in Equation 29 is the sign of the mutual inductance M between the loops L_1 and L_2 . A curve predicated on Equation 27 and indicating the response characteristics across the terminals $B-B$ of the system in Fig. 2, is substantially similar to the curve III of Fig. 4. As noted above, however, the circuit element C_2 in the system of Fig. 2 permits greater latitude in the occurrence of f_0 with respect to f_{01} , as compared to the system of Fig. 1, which does not include this element. In the system of Fig. 2, as shown by Equation 29, f_0 can be made to occur either above or below f_{01} , regardless of the polarity of the mutual coupling between L_1 and L_2 .

Thus in the system of Fig. 2 let it be assumed that one of the generators E_1 or E_2 is reversed. The equation corresponding to Equation 29 becomes

$$f_0 = f_{01} \sqrt{\frac{1 + \frac{C_1}{C_2}(N+1)}{1 \pm A}} \quad (30)$$

It is seen, therefore, that the system represented by Equation 30 effects an occurrence of f_0 at a frequency higher than f_{01} .

With reference to Fig. 3 there is shown a further modification of the invention. In this system the loops L_1 and L_2 are not in direct electrical connection, the electrical energy from L_1 being transferred to L_2 by the common inductance M between the two loops. The primary loop circuit includes L_1 and C_1 connected in series, and the secondary loop includes only L_2 . The signal response is taken off across L_2 , to the utilization circuit, which is suitably connected with a radio receiving apparatus in a manner similar to that hereinabove described in connection with the systems of Figs. 1 and 2. The operation of the system of Fig. 3 is essentially the same as the operation of the systems of Figs. 1 and 2.

The system of Fig. 3 may be operated to effect a uniform or flat signal response over a given frequency range which is substantially similar to that indicated in curve III of Fig. 4. However this flat gain can only be obtained when the mutual M between L_1 and L_2 is of plus sign and the induced voltages E_1 and E_2 are in phase opposition. The fundamental equations relating to this system are

$$E_1 = I_1 Z_1 + I_2 j w M \quad (31)$$

$$- E_2 = I_1 j w M + I_2 Z_2 \quad (32)$$

$$I_2 = - \frac{E_2 Z_1 + E_1 j w M}{Z_1 Z_2 + w^2 M^2} \quad (33)$$

The relations expressed in Equation 33 can only be satisfied when the loops L_1 and L_2 are arranged substantially in coplanar relation and these relations do not hold when the loops approach a relatively coaxial position. This distinction is consistent with the conditions above noted and specified in Equations 31 and 32, namely a positive mutual M and opposing voltages E_1 and E_2 . When these conditions in Equations 31 and 32 are not satisfied f_0 will occur at a frequency higher than f_{01} . It is thus seen that the coplanar relation indicated in Equations 31 and 32 will provide for an occurrence of f_0 at a frequency which may be either above or below f_{01} , depending upon the polarity of the induced voltages and the sign of the mutual M between the loops.

In all of the above equations relative to the antenna systems illustrated in Figs. 1, 2 and 3, it has been assumed that the angles θ_1 and θ_2 , between the plane of each loop L_1 and L_2 , respectively, and the incident wave, were identical and equal to zero. It is to be understood, therefore, that any changes in the angular positioning of the loops L_1 and L_2 with respect to the incident wave and with respect to each other, will effect important changes in the occurrence of f_0 with respect to f_{01} as is most clearly exemplified in Equations 13 and 14. These changes may be readily effected in the systems of Figs. 1, 2 and 3 by arranging the loops L_1 and L_2 , thereof, as shown in Fig. 5.

With reference to Fig. 5, L_2 is fixedly mounted to a suitable portion of the radio frame 19 with L_1 hinged as at 21 to the loop L_2 so as to be rotatable about L_2 in an arc of at least 180° . It is readily apparent that rotation of L_1 with respect to L_2 will operate to eliminate certain stations which lie either above or below f_{01} .

The invention thus provides for a compact self-contained loop antenna system which provides maximum attenuation at intermediate frequencies and a relative uniform response to signals over a range of frequencies to be received. It is to be noted also that substantially complete attenuation may be provided at a particular frequency at which the radio receiver is sensitive and substantially less attenuation at other frequencies to which the receiver is responsive. Reso-

nance of the system may be obtained by a variation of the capacitance C_3 with the inductor L_3 fixed, by a variation of the capacitance C_3 with L_3 out of the circuit and L_2 suitably increased to provide the necessary inductance, or by a variation of the inductor L_3 with the capacitance C_3 fixed, without affecting the efficient operation of the system. The antenna system of this invention is thus seen to be very flexible in its application and adapted to effect operating characteristics in correspondence with a particular troublesome receiving difficulty so as to counteract or eliminate such difficulty.

It is to be understood that only specific embodiments of the invention have been illustrated and described herein and that modifications and alterations in the arrangement of the invention may be made without departing from its full intended scope, as defined by the claims which are appended hereto.

I claim:

1. A radio antenna system including a pair of loops having different inductive characteristics, with said loops connected in series, and a condenser of fixed capacity connected in series with said loops, said loops and condenser being connected to effect complementary operating characteristics, the combined effect of such operating characteristics providing for maximum attenuation at a particular undesired frequency and for a substantially flat signal response over a desired group of frequencies, and a utilization circuit having an inductor and a capacitor connected across the loop of lower inductance and adapted to effect resonance of said antenna system by varying at least one of the elements in said circuit.

2. A radio antenna system including a pair of loops of different inductive characteristics connected in series, and a condenser in series with the loop of larger inductance, said loops and condenser and the connections therebetween providing for a signal response across the loop of lower inductance which is relatively uniform over a larger group of frequencies and attenuated over a restricted group of frequencies, and a second condenser connected between said loops and in series with said first condenser, said second condenser being adapted to vary the coupling between said loops to effect a shifting of said restricted group of frequencies relative to said larger group of frequencies.

3. A radio antenna system including a pair of loops of different inductive characteristics connected in series, and a condenser in series with the loop of larger inductance, a second condenser connected between said loops and in series with said first condenser, and a utilization circuit having an inductor and a capacitor connected across the loop of lower inductance for tuning said antenna system by varying at least one of the elements in said utilization circuit.

DAVID E. SPARKS.
